PROCESS FOR PREPARING 3-PYRIDINOLS

Niels Konrad Friedrich Wilhelm Clausen-Kaas, Haifa,
Israel, and Niels Elming, Copenhagen, DenmarkNo Drawing. Application November 29, 1954,
Serial No. 471,896.

Claims priority, application Denmark November 30, 1953

8 Claims. (Cl. 260—297)

The present invention relates to the preparation of 3-pyridinols. 15

3-pyridinol and various 2-alkyl-3-pyridinols have already been described in earlier publications, but the present invention makes it possible to produce these compounds in a simpler manner and with better yields than heretofore.

According to the invention, 3-pyridinols are produced by oxidizing to produce 2,5-dialkoxy furans, a compound of the formula

in which R is hydrogen or alkyl; for instance methyl, the amino group being, if desired, protected by conversion to the corresponding acylate, carbamate or mono- or diureid, whereupon the product is subjected, if desired, after a preceding saponification, to hydrolysis by being stored or heated in an acid or neutral medium, a pyridine ring being formed due to condensation.

According to a preferred embodiment of the invention, the compound of the above formula has its amino group protected as mentioned above and is oxidized in a solution in an alcohol by electrolysis in the presence of an electrolyte which is soluble in the alcohol employed, for instance, ammonium bromide, lithium bromide, a mixture of these two, sulfuric acid, boron trifluoride or an organic boron trifluoride complex such as boron trifluoride etherate or boron trifluoride acetic acid complex; a nitrate, a thiocyanate or a formate. The electrolyte may also be an organic halogen salt such as for instance, morpholine hydrobromide.

The alcohol used in the electrolysis is preferably methanol, as the aforesaid electrolytes are readily soluble in methanol and the electrolysis runs smoothly and at a satisfactory rate when carried out in this alcohol. However, good results are obtained also with for instance, ethanol, 2-ethoxy ethanol, etc.

The electrolysis is carried out in a manner known per se, for instance, using the apparatus described in: Acta Chem. Scand. 6, 1952, page 531, or using the apparatus described in: Acta Chem. Scand. 7, 1953, page 234.

The electrolysis should be carried out at a temperature of between 0° C. and -30° C., preferably at about -15° C. As a rule, a terminal voltage of about 3 to 20 volts is sufficient. The current strength may vary within wide limits depending on the desired oxidation rate. This is due to the fact that the starting materials used according to the invention are comparatively stable. However, the current strength should preferably lie within the range of from 0.1 to 10 amperes.

According to another embodiment of the invention, the compound of the above formula, if desired, protected as stated above, is oxidized for a few minutes to a half an hour or more, with chlorine or bromine in an anhydrous alcohol, preferably methanol, at a low temperature, for

2

instance, at -10° C. to -30° C. and preferably at about -20° C., with a simultaneous or subsequent addition of a neutralizing agent such as potassium acetate or sodium acetate.

After having been oxidized in either of the above-described ways the oxidation product may be converted to the desired 3-pyridinols either by alkaline saponification in a manner known per se, with subsequent hydrolysis, or by hydrolysis alone. It has been found that such oxidation products in which the amino group is protected by an acyl group, such as an acetyl group, should preferably be converted to 3-pyridinol by the first-mentioned process i. e., by saponification and hydrolysis, preferably in an acid medium. However, the hydrolysis may also be carried out in a neutral medium at a higher temperature. On the other hand, it has been found that oxidation products having their amino group protected by conversion to the carbamate, or mono- or diureid, will give 3-pyridinols in especially good yields when subjected to direct hydrolysis in an acid medium. This reaction is preferably carried out by boiling with a dilute inorganic acid, for instance, hydrochloric acid, sulfuric acid, hydrobromic acid etc., preferably at an acid concentration of 0.5-n to 2-n.

After said saponification and hydrolysis, or hydrolysis alone, the reaction mixture is evaporated to dryness. In the first case, pure 3-pyridinol hydrochloride is obtained, while in the latter case the free 3-pyridinol is obtained by an addition of, for instance, potassium or sodium carbonate, the 3-pyridinol then being isolated by extraction with a suitable solvent, such as, for instance, ether.

According to one embodiment of the invention, the oxidation may also be achieved directly by rapidly supplying chlorine or bromine to an aqueous alcohol, preferably methanol or ethanol, containing water in an amount of 20-90%, preferably 40-80%; this step being carried out at a low temperature, a suitable range being from -10° C. to -80° C. and preferably from -20° C. to -80° C. for a short period of time (about 5-30 minutes). More water (about 30-60%, calculated on the volume of the reaction mixture) is preferably added, and the mixture is again boiled for a short time (10-30 minutes), whereupon the 3-pyridinol is isolated. The isolation may be carried out by precipitation with, for instance, potassium or sodium carbonate, whereupon the precipitated 3-pyridinol is either filtered off or recovered by extraction, for instance, with ether.

According to still another embodiment of the invention, the starting material need not be a furan derivative substituted in the 2-position by an α -aminoalkyl group but may be substituted in this position by a group which after the oxidation of the furan derivative to a 2,5-dialkoxy-2,5-dihydrofuran is converted to an α -aminoalkyl group. This way of carrying out the steps in inverse order is within the scope of the present invention.

The invention is illustrated by the following examples:

Example 1.—6.96 gms. of 2-acetamidomethyl-2,5-dimethoxy-2,5-dihydrofuran (produced as described in Acta Chem. Scand. 6 (1952), page 667) are refluxed for 16 hours with 100 mls. of 3-N sodium hydroxide solution. The reaction mixture is then continuously extracted with ether. The ether extract yields 4.72 gms. of 2-amino-methyl-2,5-dimethoxy-2,5-dihydrofuran which are then refluxed for 15 minutes with 54 mls. of 1-N hydrochloric acid. The resulting solution is evaporated in vacuo to dryness, and the residue is dissolved in ethanol. Crystallization gives 3.63 gms. of 3-pyridinol hydrochloride (M. P. 105-107° C.), corresponding to a 93% yield obtained by the hydrolysis under acid conditions.

Example 2.—4.04 gms. of 2-acetamidomethyl-2,5-dimethoxy-2,5-dihydrofuran are refluxed for 15 minutes with 22 mls. of 1-N hydrochloric acid whereupon the resulting solution is evaporated in vacuo to dryness. The

residue is purified; the amine is then liberated and gives 0.98 gm. of 3-pyridinol (corresponding to a 52% yield) melting at 125° C.-126° C.

Example 3.-19.4 gms. of furfurylamine and 6.6 gms. of urea are refluxed for one hour. The crystalline reaction product is dissolved in a solution of 5.0 gms. ammonium bromide in 260 mls. of methanol whereupon the solution is electrolysed, for instance, in the manner as described in the British Patent No. 682,736, 11.9 ampere-hours being required. The electrolyte is poured into a solution of sodium methylate (1.2 g. of sodium in 20 ml. of methanol) and is evaporated in vacuo. The residue is refluxed for 15 minutes with 240 mls. of 1-N hydrochloric acid and is then evaporated to dryness. The residue obtained is admixed with 22 gms. of potassium carbonate, whereupon water is added. The 3-pyridinol is liberated in an amount of 16.1 gms. which corresponds to 85% of the theoretical yield.

Example 4.-15.6 gms. of 2-acetyl furanoxime are dissolved in 200 mls. of anhydrous ethanol to which 26.5 mls. of acetylchloride already have been added. The solution is shaken for four hours with 6.5 gms. of palladium charcoal (10%) under gaseous hydrogen at a pressure of 15 atmospheres. After filtration, the solvent is distilled off in vacuo, the residue is adjusted to alkaline reaction, and is then extracted with ether. The ether extract yields 6.5 gms. of 2-(α -aminoethyl)-furan which is a colourless liquid; boiling point: 148-149° C., and $n_D^{25}=1.4748$.

6.12 gms. of 2-(α -aminoethyl)-furan are dissolved, with cooling, in 9.5 mls. of 5-N hydrochloric acid to which is added a solution of 3.45 gms. urea in 16 mls. water, whereupon the mixture is refluxed for 16 hours. Upon cooling, filtration, washing twice with water and drying, 4.24 gms. (50%) of 2-(α -ureidoethyl)-furan are obtained. On recrystallization from ethyl acetate, the product is obtained in a yield of 2.96 gms. of white crystals melting at 114-116° C.

340 milligrams of 2-(α -ureidoethyl)-furan are dissolved in a solution of 150 mgs. of ammonium bromide in 10 mls. of methanol whereupon the mixture is electrolyzed in the apparatus described in Acta Chem. Scand. 7 (1953), page 234, 0.13 ampere-hour being required. After the electrolysis, the mixture is poured into a solution of sodium methylate (produced from 37 mgs. of sodium and 4 mls. of methanol). Then the product is evaporated in vacuo, the residue is refluxed for 15 minutes with 22 mls. of 1-N hydrochloric acid, and the resulting product is treated further as in Example 1. Upon purification 200 mgs. (62%) of 2-methyl-3-pyridinol hydrochloride are obtained; melting point: 225-227° C.

Example 5.-2-(carbomethoxyamidomethyl)-furan is produced from furfuryl amine according to the method described in Org. Syntheses, collective volume 2 (1943), page 278. The substance is a colorless liquid; boiling point: 122-123° C. at 10 mm. of mercury, and $n_D^{25}=1.4851$.

31.0 gms. of 2-(carbomethoxyamidomethyl)-furan are electrolyzed according to the method described in Acta Chem. Scand. 6 (1952), page 667, 11.8 ampere-hours being required, representing 110% of the theoretical consumption. In this manner 38.7 gms. (89%) of 2,5-dimethoxy-2-carbomethoxyamidomethyl-2,5-dihydrofuran are obtained as a colorless liquid; boiling point at 0.2 mm. of mercury: 104-107° C., and having $n_D^{25}=1.4652$. Then 4.34 gms. of this compound are refluxed with 22 mls. of 1-N hydrochloric acid, and upon a further treatment in the same manner as in Example 3, there will be obtained 1.45 gms. (76%) of 3-pyridinol.

Example 6.-12.5 gms. of 2-acetyl furanoxime are hydrogenated as described in Example 4. The reaction mixture is filtered and evaporated in vacuo to dryness. The evaporation residue is dissolved in 20 mls. of water, extracted with ether and reacted with 9.5 gms. of chloroformic methylester (ClCOOCH_3) as described in Org.

Syntheses, collective volume 2 (1943), page 278. In this manner 9.2 gms. (54%) of 2-(α -carbomethoxyamidomethyl)-furan are obtained as a colorless liquid; boiling point: 72°-75° C. at 0.1 mm. of mercury, and $n_D^{25}=1.4805$. Then 11.6 gms. of this compound are electrolyzed according to the method described in Acta Chem. Scand. 6 (1952), page 657, 4.1 ampere-hours being required (110% of the theoretical consumption). In this manner 13.8 gms. (88%) of 2,5-dimethoxy-2-(α -carbomethoxyamidomethyl)-2,5-dihydrofuran are obtained as a colorless liquid; boiling point: 98-102° C. at 0.2 mm. of mercury, and $n_D^{25}=1.4649$. Then 2.31 gms. of this compound are refluxed for 1.5 hours with 100 mls. of 1-N hydrochloric acid, whereupon the mixture is evaporated, and the residue further treated and purified as described in Example 1. The yield obtained is 1.05 gms. (72%) of 2-methyl-3-pyridinol hydrochloride.

Example 7.-12.5 gms. of 2-acetyl furanoxime and 30 mls. of acetic anhydride are shaken with 1.6 gms. of Raney nickel under gaseous hydrogen at a pressure of 100 atmospheres and at 70°-80° C. On distillation of the reaction mixture 9.8 gms. (64%) of 2-(α -acetamidoethyl)-furan are obtained as a light yellow liquid; boiling point: 86°-89° C. at 0.1 mm. of mercury, and $n_D^{25}=1.4922$. This compound may also be obtained by acetylation of 2-(α -aminoethyl)-furan, the production of which is described in Example 4.

2.00 gms. of 2-(α -acetamidoethyl)-furan, 0.30 gm. of ammonium bromide and 20 mls. of methanol are electrolyzed by the method described in Acta Chem. Scand. 7 (1953), page 234, 0.77 ampere-hour being required (110% of the theoretical consumption). In this manner 2.47 gms. (88%) of 2,5-dimethoxy-2-(α -acetamidoethyl)-2,5-dihydrofuran are obtained as a colorless liquid; boiling point: 110-115° C. at 0.1 mm. of mercury, and $n_D^{25}=1.4739$. Then 2.15 gms. of this compound are saponified in an alkaline medium as described in Example 1, there thus being obtained 1.39 gms. (80%) of 2,5-dimethoxy-2-(α -aminoethyl)-2,5-dihydrofuran as a colorless liquid; boiling point: 90°-92° C. at 12 mm. of mercury, and $n_D^{25}=1.4565$. Then 1.10 gms. of this compound is hydrolyzed and condensed in an acid medium, whereupon the product is further treated as described in Example 1. The yield obtained is 0.88 gm. (95%) of 2-methyl-3-pyridinol hydrochloride.

Example 8.-2.78 gms. (0.020 mol) of 2-(α -acetamidoethyl)-furan (prepared by acylation of furfurylamine) and 4.00 gms. (0.041 mol) of potassium acetate were dissolved in 24 mls. of anhydrous methanol. The mixture was cooled to -20° C., and a solution of 1.00 ml. (0.020 mol) of bromine in 20 mls. of anhydrous methanol was added at -20° C. during 5 minutes, with efficient stirring. The stirring was continued for 10 minutes and the mixture evaporated in vacuo. 200 mls. of anhydrous ether were added to the residue, the potassium bromide was removed by filtration, and the filtrate was distilled in vacuo. The yield was 3.21 gms. (80%) of 2,5-dimethoxy-2-(α -acetamidoethyl)-2,5-dihydrofuran, B. P._{0.1} 120°-140° C. The product crystallized partly on standing.

$\text{CsH}_6\text{ON}(\text{COCH}_3)(\text{OCH}_3)_2$. Calc.: C, 53.7; H, 7.5; N, 7.0; OCH_3 , 30.9; COCH_3 , 21.4. Found: C, 53.9; H, 7.7; N, 7.3; OCH_3 , 30.7; COCH_3 , 21.3.

The resulting product was then converted to 3-pyridinol as described in the Examples 1 and 2.

Example 9.-0.97 gm. (0.010 mol) of furfurylamine and 0.33 gm. (0.0055 mol) of urea were mixed and refluxed (1 hour) in an oil bath (190°-200° C.). The reaction product was dissolved in a solution of 2.00 gms. (0.0204 mol) of potassium acetate in 13 mls. of anhydrous methanol, and the mixture was cooled to -20° C. A solution of 0.50 ml. (0.010 mol) bromine in 10 mls. of anhydrous methanol was added at -20° C. during 5 minutes, with efficient stirring. The stirring was continued for 10 minutes, and the mixture was evaporated

in vacuo. 12 mls. of 1-N hydrochloric acid were added, and the mixture was refluxed for 15 minutes. The 3-pyridinol was isolated as described in Example 3. The yield was 0.65 gm. (68%), M. P. 122-124° C. (Hershberg apparatus, corr.).

Example 10.—9.7 gms. (0.1 mol) of furfurylamine were dissolved in 50 mls. water and 40 mls. methanol. Then 4.28 mls. chlorine, saturated at -80° C. (0.1 mol) was passed into the solution at -60° C. to -80° C. for 5 minutes. The light yellow semisolid reaction mixture was heated to boiling. 20 mls. of water were added and the dark red solution evaporated to a volume of about 50 mls. After cooling, 13.8 gms. (0.1 mol) of anhydrous potassium carbonate were added, a brown precipitate of impure 3-pyridinol was removed by filtration, washed once with water and dried. The yield was 4.94 gms. from which 4.25 gms. (45%) of 3-pyridinol (colorless crystals) were obtained by sublimation.

Example 11.—9.7 gms. (0.1 mol) of furfurylamine were dissolved in 70 mls. water and 30 mls. methanol. A solution of 5.0 mls. (0.1 mol) of bromine in 50 mls. methanol, cooled to -80° C., was added at -50° C. to -80° C. during 1 minute. The light yellow reaction mixture was heated to 0° C., 50 mls. of water were added, and the methanol was removed in vacuo. The remaining aqueous solution was refluxed for 15 minutes whereby the solution became dark red. The solution was evaporated to dryness in vacuo. The dark residue was dissolved in 50 mls. of methanol. 500 mls. of ether were added, and a precipitate of 3-pyridinol hydrobromide was removed by filtration and dried (13.2 gms.). 70 mls. water and 13 gms. potassium carbonate were added, and the mixture was continuously extracted with ether. In this manner 6.6 gms. (70%) of pyridinol (almost white crystals) were obtained.

Example 12.—9.7 gms. (0.1 mol) of furfurylamine were dissolved in 100 mls. water, and a cooled solution of 5.0 mls. (0.1 mol) of bromine in 20 mls. ethanol was added during 10 seconds with stirring at -20° C. The almost colorless reaction mixture was heated to boiling and evaporated to a volume of about 50 mls. After cooling, 13.8 gms. (0.1 mol) of potassium carbonate were added to the dark red solution. A brown precipitate of impure 3-pyridinol was removed by filtration, washed once with water and dried. The yield was 8.0 gms. from which 6.3 gms. (66%) of 3-pyridinol (colorless crystals) were obtained by sublimation.

Example 13.—10.5 gms. of 2-carbomethoxy-5-isopropylfuran are dissolved in 45 mls. of methanol to which 0.375 gm. of concentrated sulfuric acid have been added. The solution is then electrolyzed in the apparatus described in Acta Chem. Scand. 7 (1953), page 234. 4.20 ampere-hours being required (125% of the theoretical consumption). After the electrolysis, the reaction mixture is poured into sodium methylate (175 mgs. of sodium in 7 mls. of methanol), whereupon the methanol is evaporated in vacuo and to the residue are added 50 mls. of dry ether. After filtration and distillation 12.5 gms. (86%) of 2,5-di-methoxy-2-carbomethoxy-5-isopropyl-2,5-dihydrofuran are obtained as a colorless liquid; boiling point: 71° - 75° C. at 0.1 mm. of mercury, and $n_{D}^{25} = 1.4498$. Then 3.45 gms. of this compound are mixed at -50° C. with a solution of 2.2 mls. ammonia (measured at -80° C.) and 0.3 ml. of water in 6 mls. of methanol. The resulting solution is allowed to stand for 7 days at room temperature and is then evaporated in vacuo. The residue is dissolved in dry ether whereupon the solution is evaporated to dryness, finally at 0.1 mm. of mercury, to remove traces of water and methanol. The residue obtained is dissolved in 90 mls. of ether, and the solution is added dropwise, with stirring, to a mixture of 0.97 gm. of lithium aluminum hydride in 60 mls. of ether. After having been stirred for 20 hours at room temperature, the mixture is cooled to -20° C., whereupon 20 mls. of water and then 25 mls. of 25% sodium

hydroxide solution are added dropwise. The mixture is extracted continuously with ether. The ether extracts are dried with magnesium sulfate and then distilled, there thus being obtained 2.13 gms (71%) of 2,5-dimethoxy-2-amino-methyl-5-isopropyl-2,5-dihydrofuran as a colorless liquid; boiling point: 121-126° C. at 13 - 12 mm. of mercury, and $n_{D}^{25} = 1.4625$. Then 1.50 gms. of this compound is refluxed for 15 minutes with 17 mls. of 1-N hydrochloric acid, whereupon the product is evaporated to dryness in vacuo. The evaporation residue is dissolved in 10 mls. of water, and then 1.0 g. of potassium carbonate are added. The mixture is extracted continuously with ether. The ether extract yields 0.71 gm. (69%) of 6-isopropyl-3-pyridinol melting at 155-157° C.

15 While the invention has been described and exemplified with respect to furan starting materials, which are not substituted in the 3- and 4-position, it is to be understood that in its broader aspects, the starting material may comprise, after oxidation of the corresponding 2-(α -amino-alkyl)-furans, a furan compound having the general formula:

30 where R represents hydrogen or an alkyl group, including a cycloalkyl group, R1 represents alkyl or cycloalkyl groups of not more than 6 carbon atoms, and R2, R3 and R4, which may be alike or different, represent hydrogen or substituents, which are not attacked by the said oxidation, e. g. alkyl, substituted alkyl, including hydroxalkyl and acyloxyalkyl, aryl, substituted aryl, aralkyl, carboxyl, esterified carboxyl, carbamidoalkyl, halogen and nitro groups. Preferably R1 represents methyl groups.

35 The process then proceeds according to the following scheme of reaction:

45 in which R, R1, R2, R3 and R4 have the meanings assigned immediately above.

50 The invention further comprises a method in which the above reaction is one of the steps, the starting material being an amide of the general formula:

wherein R5 is a radical of the general formula:

65 wherein R, R1, R2, R3 and R4 have the above significance, and R6 is an alkyl, alkoxy, amino or substituted amino group, or an R5-group. By acid hydrolysis, or by saponification followed by acid hydrolysis, the amine is first liberated and then converted into the 3-pyridol according to the above reaction scheme.

70 Reference is made to applicants' co-pending divisional application, Serial No. 547,888, filed November 1, 1955.

We claim:

75 1. A method of producing 3-pyridinols comprising reacting with an aliphatic alcohol under oxidizing condi-

tions to produce a 2,5-dialkoxy furan, a compound of the formula

in which R is selected from the group consisting of a hydrogen atom and an alkyl group and hydrolyzing the resulting product at a pH at least as low as 7 to form a 10 pyridine ring by condensation.

2. The method of claim 1 in which said compound has the amino group protected by conversion to a derivative selected from the group consisting of acylates, carbamates, monoureids and diureids.

3. The method of claim 1 in which the alcohol is methanol.

4. The process of claim 1 in which the oxidation is carried out electrolytically in the presence of an electrolyte soluble in the alcohol.

5. The process of claim 4 in which the oxidation is carried out at a temperature between 0° C. and -30° C.

6. The process of claim 2 in which said oxidation is carried out with a halogen selected from the group consisting of chlorine and bromine in anhydrous methanol.

7. The process of claim 1 in which the oxidation is carried out with chlorine or bromine in an aqueous alcohol solution.

8. The process of claim 7 in which said alcohol is selected from a member of the group consisting of ethanol and methanol.
